(57) CLAIM

The ornamental design for a pen and highlighter, as shown and described.

DESCRIPTION

FIG. 1 is a perspective view showing our design for a pen and highlighter;

FIG. 2 is a left side view of the pen and highlighter of FIG. 1, the right side view being a mirror image thereof;

FIG. 3 is a front view of the pen and highlighter of FIG. 1; FIG. 4 is a rear view of the pen and highlighter of FIG. 1; FIG. 5 is a bottom plan view of the pen and highlighter of FIG. 1;

FIG. 6 is a top plan view of the pen and highlighter of FIG. 1; and,

FIG. 7 is an exploded front view of the pen and highlighter of FIG. 1.

The dashed lines are for illustrative purposes only and form no part of the claimed design.
